J. W. BRADY.
LOOSE LEAF HOLDER.
FILED MAY 29, 1922.

INVENTOR:

Patented Dec. 19, 1922.

1,439,140

UNITED STATES PATENT OFFICE.

JOSHUA W. BRADY, OF ST. PAUL, MINNESOTA.

LOOSE-LEAF HOLDER.

Application filed May 29, 1922. Serial No. 564,324.

To all whom it may concern:

Be it known that I, JOSHUA W. BRADY, a citizen of the United States, residing at St. Paul, in the county of Ramsey and State of Minnesota, have invented certain new and useful Improvements in Loose-Leaf Holders, of which the following is a specification.

My invention relates to loose leaf holders of the kind adapted to be supported either 10 on a desk or table or by one of the operator's hands and firmly yet detachably holds one or more sheets to be written on, and the object is to improve such a device by new parts and features as will now be described.

15 In the accompanying drawing:

Fig. 1 is a perspective view of my improved leaf holder partly opened and with some loose leaves placed on it.

Fig. 2 is an edge view of the device further 20 opened than in Fig. 1.

Fig. 3 is a top view of the device in folded or closed position.

Fig. 4 is a section on line 4—4 in Fig. 3.

Fig. 5 is a top or plan view of the head 25 end of the device with all canvas and lever omitted showing how the springs, when more than one is used, may be arranged and connected to a metal strip.

Fig. 6 is an edge view of the upper side 30 of Fig. 5 looking in the direction of arrow A in Figs. 5 and 2, with the lever restored.

Fig. 7 is an enlarged face view of the combined card holder and lever by which the clasp of the device is opened during the in- 35 sertion of the loose leaves.

Fig. 8 is an end view of Fig. 7.

Referring to the drawing by reference numerals, 10 designates the usual flat, stiff body upon which the leaves 11, to be written on, 40 are placed. In the curved head end 12 of said body are imbedded one or more leaf springs 13, bent to about triangular form (see dotted lines 13 in Figs. 2 and 3) or they may be of any desired curvature so that each 45 of them forms a lower clasping arm or jaw 14 and an upper clasping arm 15. The latter arm tends at all times to hold the leaves 11 inserted firmly upon the body 10.

16 is a flat, stiff cover adapted to rest upon 50 the leaves 11 to protect them when the device is not in use. This cover is formed with sections 16^a, 16^b connected by joints 17, 18, 19 to enable it to be folded over the head end 55 of the device and thence under the body 10 when so desired, as shown in dotted line 16, 16^a in Fig. 2.

In order to readily open the clasping jaws of the device during the inserting of the loose leaves I employ a short, flat lever 20, which has one end pivoted at 21 either to 60 one of the springs 13, as in Fig. 3, or as in Figs. 5 and 6, to a metal strip 22 bridging the space between the two springs and riveted to the latter at 23. Said strip 22 may extend more or less into the springs or 65 even through and beyond them forming projections 22^a, see Fig. 5, which like an adjoining strip 24, of wood or fiber, serve to reinforce the canvas 25 with which the device is covered and which may form the joints 17— 70 18—19. In Fig. 6 is shown that the strip or plate 22 may be offset upwardly between the ends of the two springs to form a straight face where the lever 20 is placed. Yet, as a rule, the lever is slightly spaced from the 75 canvas by a washer 26, and the swinging end of the lever when idle rests on a wearing plate 27.

The lever 20 is composed of a solid plate 28 (see Figs. 7 and 8) which has one end 80 placed on pivot 21 and may be slightly channeled as in Fig. 8. Frictionally but slidably engaging over the edges of plate 28 are the bent over longitudinal edges 29 of a plate 30. The latter has a sight opening 31 through 85 which to read a card 32 which is slidably inserted between the two plates or lever members and serves to indicate the class of written matter contained in the file and any other useful information desired to be placed 90 on the device.

In the making of the device it is obvious that for a simple, cheap make there may be only one of the springs 13 between the left and right edge of the device and the lever 95 pivoted to such single spring. And the lever may be a plain or solid metal strip. When two springs are used the strips 22, 24, may be much modified and as shown in Fig. 3 the lever may be pivoted to only one of the 100 two springs, for when the article is finished the springs and any strips inside of them and the canvas pasted over as a finish, form a single wing or upper clasping jaw to which the lever 20 may be pivoted at any suitable 105 point and will operate.

In the use of the device the operator, when ready to insert some loose leaves in the device, turns the lever 20 upward and rearward and opens the clasp by pressing either 110 directly on the lever as the finger 33 in Fig. 1 or he may press on the small cover section

16^a, and thereby on the lever 20, as in Fig. 2 and after the leaves are inserted the lever 20 is released from pressure and swung down to the folded position shown in full line in Fig. 3.

5. Fig. 3.

What I claim is:

1. A loose leaf holder comprising in combination, a flat body for the loose leaves to rest on, said body having at one end an upwardly and inwardly curved resilient jaw for holding the loose leaves against the body, a cover hingedly connected with the jaw and adapted to rest upon the body and the leaves thereon, said cover having also near 10 said jaw joints enabling it to be folded over the jaw and up to the under side of the body, and a flat lever pivoted with one end to said jaw and normally folded in longitudinal direction of the adjacent joints of the cover 15 but swingable rearwardly therefrom to serve 20 as a lever to press on in opening the jaw

when loose leaves are to be inserted or removed.

2. The structure specified in claim 1, said lever having a space adapted for holding 25 a card, and a sight opening through which to read the contents of the card.

3. The structure specified in claim 1, said lever being spaced from the jaw by a washer about its pivot.

4. The structure specified in claim 3, and a 30 wearing plate fixed on the jaw to prevent the swinging end of the lever from chafing the finished surface of the jaw.

5. The structure specified in claim 1, 35 said jaw comprising two spaced springs and a flat bar secured thereto and bridging the space between the springs, said lever being pivoted to said bridging bar.

In testimony whereof I affix my signature, 40

JOSHUA W. BRADY.
